The ornamental design for a composite overcap and delivery head for a container, as shown and described.

DESCRIPTION

FIG. 1 is a top plan view of a composite overlap and delivery head for a container, showing my new design in the opened position;

FIG. 2 is a top plan view thereof, shown in the closed position;

FIG. 3 is a bottom plan view thereof;

FIG. 4 is a side elevational view of FIG. 1, the opposite side view being a mirror image thereof;

FIG. 5 is a rear elevational view thereof;

FIG. 6 is a front elevational view thereof;

FIG. 7 is a side elevational view similar to FIG. 4, showing the design in the closed position;

FIG. 8 is a rear elevational view similar to FIG. 5, showing the design in the closed position; and,

FIG. 9 is a front elevational view similar to FIG. 6, showing the design in the closed position.
